UNITED STATES PATENT OFFICE.

JOSEPH LUNEPP, OF SOUTH RIVER, NEW JERSEY.

TEXTILE-FINISHING DRUM.

1,377,900.

Specification of Letters Patent. Patented May 10, 1921.

Application filed April 7, 1920. Serial No. 371,912.

To all whom it may concern:

Be it known that I, JOSEPH LUNEPP, a citizen of the United States, and a resident of South River, county of Middlesex, and 5 State of New Jersey, have invented a new and Improved Textile-Finishing Drum, of which the following is a full, clear, and exact description.

This invention relates to mechanism for 10 the manufacture of textiles, and has reference more particularly to a finishing drum for the treatment of laces and embroideries.

An object of this invention is to provide 15 a finishing drum upon which lace or embroidery may be wound for the final treatment in various solutions, followed by drying.

Another object of this invention is to 20 provide a finishing drum of the class indicated which will prevent the lace which is wound upon it, from shrinking as the result of treatment in the various solutions and drying.

Reference is to be had to the accompanying 25 drawing forming a part of this specification, in which it is understood that the drawing illustrates only one form of the invention, and in which—

Figure 1 is a side view of a textile solution 30 tank with parts broken away to disclose the construction of my improved device.

Fig. 2 is a central sectional view on a large scale through the finishing drum.

Fig. 3 is a fragmentary elevation of the 35 finishing drum.

Fig. 4 is a sectional perspective view on a large scale of one of the slats which are used in my preferred form of finishing drum in which the slat is covered with metal such as 40 copper.

Fig. 5 is a sectional perspective view of a modified form of slat in which the same is not covered.

Fig. 6 is a second modified form of a slat 45 which is circular in cross section.

Referring to the accompanying drawing by numerals, 10 indicates a textile solution tank which is preferably rectangular in shape, and is provided with a plurality of 50 partitions 11 which divide said tank into compartments, each compartment containing a different liquid such as caustic soda, bleaching powder solution, water, etc. Each side of each compartment is provided with 55 an open bearing 12 in which is journaled a shaft 13, and said shaft is provided on one

end with a belt pulley 14 rotated from any source of power by means of a belt 15. My improved textile finishing drum is secured to said shaft 13, and is of such length as to 60 be contained between the walls of each compartment, and the bearing 12 is of such height that the drum will dip into the solution contained in said compartment. The drum consists of a pair of annular supports 65 16 which are secured to arms 17 positioned at 90 degrees to each other, and secured together at their intersection. The shaft 13 passes through the arms 17 at their intersection, and the two annular supports 16 are 70 spaced apart at a distance equal substantially to the width of the face to be treated, by means of parallel strips 18 secured to the arms 17 of the two annular supports 75 adjacent the intersection of said arms. A plurality of slats 19 are provided with offset recesses 20 at each end which engage the annular supports 16, and said slats are secured to said supports by any suitable fastening means not shown. The slats 19 are 80 preferably rectangular in cross section with the major axis of the cross section positioned radially with respect to the shaft 13, and the outer edge of said slats are preferably 85 wedge shaped where they come in contact with the lace which is wound around the drum. This method of constructing slats is especially advantageous since when the lace or embroidery goes through a series of solutions and is finally dried, it shrinks 90 considerably, and unless the slats were stiff in the center, they would deflect and permit said shrinkage. However, with the slats shaped as shown and described, the deflection in the center of said slats will be reduced to a minimum and therefore the loss 95 due to shrinkage of the laces will be practically eliminated. I find that wood is a very good material for use in constructing my textile drum, and preferably the slats 19 are covered with a metal coating 21 which 100 may be of copper so that the wear on the slats due to continued and long use will be reduced to a minimum. I may also make my drum of metal in which case the slats 19, 105 will be of solid metal construction as shown in Fig. 5. The slats 19, may also be circular in cross section as shown in Fig. 6. My improved textile drum is convenient in operation as it may be transferred from one 110 compartment to the other by lifting it from its bearings 12.

I would state in conclusion that while the illustrated example constitutes a practical embodiment of my invention, I do not limit myself strictly to the mechanical details 5 herein illustrated, since manifestly the same can be considerably varied without departure from the spirit of the invention as defined in the appended claims.

Having thus described my invention, I 10 claim as new and desire to secure by Letters Patent:

1. In a textile finishing drum, a shaft, a pair of aligned annular supports, arms securing said supports to a shaft and spacing them 15 therefrom, a plurality of radially disposed parallel slats connecting the supports, said slats having cutaway portions at each end forming projections on the slats located against the periphery of the annular supports, and said cutaway portions forming 20

shoulders on the slats located against the inner faces of the supports, and all of said slats including tapering portions adjacent their outer edges.

2. In a textile finishing drum, a pair of 25 annular supports positioned substantially parallel and secured to a co-axially located shaft, a plurality of parallel slats secured around the peripheries of said annular supports, each of said slats being rectangular 30 in cross section with the major axis of the sections positioned radially with respect to said shaft, each of said slats also being wedge shaped on its outer edge adapted to receive textiles which are wound around 35 said slats, and means for rotating said shaft.

3. A device as described in claim 2, characterized by a metal covering associated with each of said slats.

JOSEPH LUNEPP.
